UNITED STATES PATENT OFFICE.

PATRICK J. MAHONEY, OF SHARON, PENNSYLVANIA.

SAFETY DEVICE FOR WIRE-DRAWING MACHINES.

Application filed September 30, 1925. Serial No. 59,711.

This invention relates to improvements in safety mechanisms for employment in connection with wire drawing machines. In the operation of the ordinary types of wire drawing machines, the wire to be drawn is led from a supply reel positioned at some distance from the drawing machine itself and is passed through the reducing die and drawn through the die through the rotation 10 of a take-up drum upon which the drawn wire is wound. In the operation of the machine it sometimes happens that the wire upon the supply reel becomes tangled and, as a result, this reel is forcibly drawn toward the drawing machine, frequently resulting in serious injury to the operator of the machine. Therefore, the present invention has as one of its objects to provide means whereby the rotation of the take-up 20 drum will be immediately arrested in the event of any displacement of the supply reel in the direction of the drawing machine, so that the disastrous results referred to will be avoided.

It sometimes happens that a workman operating the machine will stumble in approaching the machine, or will carelessly lean toward the take-up drum and be injured, and therefore it is another object of the invention to provide means for automatically stopping the transmission of power to the take-up drum under these conditions.

It likewise sometimes happens that the wire will fly over the storage reel or will twist or become tangled as it travels through the die, and this will likewise frequently cause injury to the operator of the machine. Therefore the invention has as another object to provide means for automatically stopping the transmission of power to the take-up reel under such conditions.

Another object of the invention is to provide means for automatically stopping the transmission of power to the take-up reel when the last portion of the wire is about to pass through the die.

In the accompanying drawings:

Figure 1 is a view in front elevation of the mechanism embodying the invention, so much of the drawing machine as is necessary to an understanding of the invention being likewise illustrated in said figure.

Figure 2 is a vertical front to rear sec-

tional view taken substantially on the line 2-2 of Figure 1, looking in the direction indicated by the arrows.

Figure 3 is a plan view of the mechanism and the part of the drawing machine with which it is associated.

Figure 4 is a fragmentary perspective view illustrating a portion of the mechanism.

Figure 5 is a view partly in elevation and partly in vertical section substantially on the line 5-5 of Figure 3 looking in the direction indicated by the arrows.

In the drawings, the bed of the wire drawing machine is indicated by the numeral 1 and the take-up drum upon which the drawn wire is wound, is indicated by the numeral 2. This drum is secured upon the shaft 3 which is rotatably mounted in a suitable bearing 4 in the bed 1 of the machine, both for rotation and upward sliding movement, and a beveled gear 5 is fixed upon the lower end of the shaft 3 and meshes with a similar gear 6 fixed upon a driven shaft 7 so that rotative movement is imparted to the shaft 3 for rotating the said drum 2 and winding the wire thereon, the wire being drawn through the reducing die which is illustrated in a general manner in the drawings and indicated by the numeral 8. The wire to be drawn is led from a supply reel indicated by the numeral 9 and this reel is mounted for free rotation upon a supporting stand 10 which stand is ordinarily located at some distance in advance of the drawing machine. The stand 10 is mounted upon a suitable base 11, in turn so mounted upon the floor of the room in which the machine is installed that the stand together with the reel supported thereby may have limited sliding movement in the direction of the machine. The numeral 9^a indicates a flexible connection which is connected at its upper end to the stand 10 and

is led downwardly over a pulley 9^b mounted at the upper end of a tubular casing 10^a which opens at its upper end through the floor and which extends beneath the floor, the flexible connection 9^a extending downwardly within the casing and being connected at its lower end to a weight 10^b which serves to normally hold the stand against sliding movement in the direction of the machine and which likewise serves as a means for returning the stand and the reel

supported thereby to its normal position if the wire, leading from the reel, has become tangled and is afterwards relieved of tension. As previously stated, the invention 5 contemplates the provision of means for automatically stopping the application of power to the take-up reel 2 in the event the wire becomes tangled about the reel 9 and a pull is exerted upon the reel in the direction of the machine, and this means will now 10 be described.

The numeral 12 indicates a rock arm which is pivotally supported at a point intermediate its ends, by a bracket 13 mounted 15 beneath the bed 1 of the drawing machine, the rear end of the arm being formed with a slot 14 receiving a pin 15 carried at the lower end of a stem 16 which extends slidably upwardly through the bed 1 and is provided at its upper end with a roller 17 which engages the under side of the lower head of the drum 2, it being understood at this point if the forward end of the rock arm 12 is depressed or lowered, the upper end will be 20 swung upwardly, thereby effecting upward movement of the stem 16 and elevation of the drum 2, thereby disengaging the gear 5 from the gear 6. This will, of course, interrupt the application of power to the shaft 3 and the drum 2 will cease to rotate.

A weight 18 is fixed upon the rock arm 12 forwardly of the pivot therefor and tends to overbalance this arm so as to effect upward swinging movement of its rear end and operation of the stem 16. Links 19 are pivotally connected as at 20, to the forward end of said rock arm and at their upper ends are connected as at 21, to a slide plate 22 which is slidably mounted in spaced guides 23 and 24 mounted upon the front of the bed of the machine. The guide 24 is provided with a slot 25, and slidably mounted in this slot is a detent 26 having a beveled end 27 presented toward one edge of the plate 22, this edge 25 of the plate being formed with a substantially V-shaped notch 28 in which the beveled end of the detent normally engages as illustrated clearly in Figure 1 of the drawings, so that the plate 22 is normally held in an elevated position and in such position that the stem 16 will be lowered to an extent to permit of coercive engagement of the gear 6 so that motion may be transmitted to the shaft 3 and, therefore, to the drum 2. At 30 this point it will be evident that if the detent 26 is shifted toward the right in Figure 1 of the drawings, its beveled end will be withdrawn from engagement in the notch 28, whereupon the plate 22 will be released and, therefore, the weight 18 will act immediately to rock the arm 12 and project the stem 16 upwardly to correspondingly shift the drum 2 and shaft 3 and thereby disengage the gear 5 from the gear 6 and effect cessation of rotation of the drum. In order to limit the

downward movement of the plate 22 and consequently limit the movement of the rock arm 12 and the stem 16, the guide 24 is provided with a shoulder indicated by the numeral 29, which is to be engaged by the upper wall of the notch 28 in the downward movement of the plate 22.

The numeral 30 indicates a rock shaft which is mounted vertically in a bearing 31 constituting a part of the guide 24, and this shaft is provided at its lower end with a crank-arm 32 which is engaged in an opening in a boss 33 formed upon the outer end of the detent 26. A spring 34 is arranged to coact with said detent to yieldably hold the same in an inwardly slid position and consequently in engagement with the slide plate 22. The shaft 30 is provided at its upper end with an arm 35 which extends in front of the bed of the machine as clearly shown 35 in Figures 1 and 3 of the drawings. The numeral 36 indicates in general a rocker which is mounted in a suitable bearing 37 upon a support 38 located in front of the machine, and the rocker is provided with an arm 39 which extends rearwardly therefrom, thence at right angles as at 40, and then upwardly to provide an arm 41 the upper end portion of which is located directly in front of the free end portion of the arm 35. A spring 42 is mounted upon the side of the support 38 and coacts with the portion 39 of the rocker 36 and normally yieldably holds the rocker in the position illustrated in Figures 1 and 3 of the drawings in which 40 position the arm 41 of the rocker will not exert any pressure against the arm 35 of the crank shaft 30. At the other side of the bearing 37, the rocker 36 is provided with an upwardly extending lever arm 43 provided at its upper end with an eye 44 through which the wire is led from the supply reel 9 to the die 8. The numeral 44' indicates a rod which is supported at one end by the stand 10 for the supply reel 9, the free end of the rod being normally presented toward and relatively close to the lever arm 43 of the rocker 36. At this point it will be evident that in the event the wire becomes entangled upon the reel 9 and a pull is exerted tending to move the reel and its stand forcibly in the direction of the machine proper the rod 44' will engage the lever arm 43 and the rocker 36 so as to cause the arm 41 of said rocker to ride against the arm 35 thereby rocking the shaft 30 and retracting the detent 26 against the tension of the spring 34 thus releasing the slide plate 22 and permitting the weight 18 to rock the arm 12 and vertically move the stem 16 to 45 elevate the drum 2 and disengage the gear 5 from the gear 6 thus arresting the application of power to the shaft by which the said drum is supported. Therefore, in such a 50 contingency, there can be no appreciable 55

movement of the supply reel towards the machine which ordinarily would cause injury to the operator of the machine.

The numeral 45 indicates in general a rocker mounted in a suitable bearing 46 upon the front of the machine and including an arm 47 which upstands in front of the outer end of the arm 35 and is normally in contact therewith. The rocker further includes an arm 48 which extends directly forwardly from the rocker and thence upwardly and has its upper end turned laterally as at 50 and supporting a grooved roller 51. A leaf spring 52 is secured at its lower end to the bed of the machine and at its upper end bears against the arm 47 of the rocker 45 and the tendency of this spring is to so act upon the rocker as to cause rearward swinging movement of the arm 47 to effect corresponding movement of the arm 35, and likewise hold the roller 51 in an elevated position and in engagement with the stretch of wire passing from the supply reel 9 to the forming die 8. So long as the wire 20 is tensioned, the roller 51 will be held in lowered position and the spring 52 will be under tension and the arm 47 of the rocker 45 will not act with force against the arm 35 of the shaft 30. However, should the 25 wire break or become slack, as for example at the moment when the last portion of the length of the wire leaves the supply reel 9, the spring 52 will immediately act to cause rocking movement of the rocker 45 and effect rearward swinging movement of the arm 47 to correspondingly move the arm 35 and thereby rotate the shaft 30 to retract the 30 detent 26, thereby permitting the plate 22 to move downwardly and enabling the weight 18 to act upon the rock arm 12 to effect upward movement of the stem 16 and disengagement of the gear 5 from the gear 6.

It will also be evident at this point that should the wire become twisted or knotted 45 after it leaves the supply reel 9 and before it reaches the die 8, the twist or knot in the wire will engage the eye 44 at the upper end of the lever arm 43 and thus effect rocking movement of the rocker 36 with the result that the detent 26 will be retracted to provide for immediate automatic operation of the mechanism to stop the application of power to the take-up drum.

In order that the wire may be suitably 50 lubricated before it reaches the die 8, a trough 53 is mounted beneath the roller 51, and any suitable lubricating material such for example as soap is placed within the trough and taken up through the rotation of the roller and supplied to the wire, the lower side of the roller rotating in the said lubricating material.

As previously stated, means is provided 55 for automatically stopping the operation of the machine in the event the operator should

stumble or lean against the front of the machine in a position where he would be subject to injury, and said means includes a rocking frame which is indicated in general by the numeral 54 and comprises spaced side members 55 having their lower portions turned at right angles to provide alined shaft portions 56 which are journaled in suitable bearings 57, located at the lower ends of the guides 23 and 24. These portions 56 are connected by a substantially U-shaped crank 58 to which is connected the upper end of a link 59, the link having a longitudinal slot 60 therein through which the pivot pin 61 for the links 19, heretofore referred to, extends. A bar 62 is supported by the upper end of the side members 55 of the rocking frame 54, and by reference to Figures 1 and 3 of the drawings it will be observed that one of the side members 55 extends upwardly in front of the arm 35. Normally the frame will occupy substantially the position shown in the drawings and it will be evident that should the operator of the machine stumble and fall toward the machine or lean against the machine his body will press against the bar 62 thereby rocking the frame 54 and causing the said side member 55 of the frame to exert pressure against the arm 35 and rock the shaft 30 to effect retraction of the detent 26 thereby releasing the slide plate 22 and permitting the weight 18 to rock the arm 12 and cause discontinuance of application of power to the take-up reel. The rocking frame 54 serves also as a means whereby the parts of the safety device may be restored to their normal position, for it will be evident that if the slide plate 22 has been released through retraction of the detent 26, and a forward pull is exerted upon the bar 62 to bring the frame 54 forwardly, an upward pull will be exerted upon the link 59 until the lower end of the slot 60 engages the pivot pin 61 whereupon the rock arm 12 will be restored to normal position and the slide plate 62 will be elevated until the beveled end of the detent reengages the notch 28.

Having thus described the invention, what I claim is:

1. In safety mechanism of the class described, the combination with the winding drum and die of a wire drawing machine, means for transmitting motion to the drum, and the supply reel and its support from which the wire to be drawn is led to the drum through the die, of automatic means for rendering the motion transmitting means inactive in the event of displacement of the reel in the direction of the die, comprising a displacing rock arm, means tending to actuate the same, a slidable member to which the arm is connected, a detent coacting with the slidable member and normally holding the same in position to restrain the arm from

- actuation, and means actuated through such displacement of the said reel for retracting the detent from engagement with the said slideable member, the last mentioned means comprising a rock shaft having a crank portion, operative connection between the detent and the crank portion of the shaft, an arm extending from the said shaft, a lever mounted for rocking movement and for co-
10 action with the arm to effect rocking of the shaft to retract the detent when the said lever is rocked on one direction, and a rigid rod connected to the reel support and operatively presented to an extension of the
15 lever to effect such rocking movement thereof, upon displacement of the reel.
2. In a safety mechanism of the class described, the combination with a winding drum and die of a wire drawing machine, means for transmitting motion to the drum, and the supply reel, and its support, from which the wire to be drawn is led to the drum through the die, of automatic means for rendering the motion transmitting means inactive in the event of displacement of the reel in the direction of the die, comprising a displacing rock arm, means tending to actuate the same, means normally restraining the arm from actuation including a slideable
25 detent, a rock shaft, operative connection between the rock shaft and the detent for effecting actuation of the detent upon rocking of the shaft in one direction, an arm extending from the rock shaft, a rocker including an arm engaging the last mentioned arm and further including a second arm, a roller carried by the second mentioned arm and normally engaged by the stretch of wire extending between the reel and the die whereby to hold the rocker in position such that the first mentioned arm thereof will be inactive with
30 relation to the arm of the rock shaft, means for automatically actuating the rocker, upon release of the said stretch of wire from tension, whereby to effect rocking of said shaft and retraction of the detent, a lever mounted for rocking movement and having a portion at one side of its pivot coacting with the arm of the rock shaft, and a rod having one end connected to the reel support whereby displacement of the reel will effect longitudinal movement of the rod, the other end of the rod being presented to an extension of the lever.
3. In safety mechanism of the class described, the combination with the winding

drum and die of a wire drawing machine, means for transmitting motion to the drum, and the supply reel from which the wire to be drawn is led to the drum through the die, of automatic means for rendering motion transmission means inactive in the event of knotting of the wire between said reel and the die, the said means comprising a displacing rock arm, means tending to actuate the same, a slideable member to which the arm is connected, a detent coacting with the slideable member and normally holding the same in position to restrain the arm from actuation, a rock shaft having a crank portion operatively connected with the detent, an arm ending from the said rock shaft, a rocker including an arm upstanding in advance of the last mentioned arm, the rocker also including an upstanding lever arm, and an eye at the upper end of the said lever arm for the passage therethrough of the wire and of a diameter to be engaged by a knot or twist in the wire.

4. In safety mechanism of the class described, the combination with the winding drum and the die of a wire drawing machine, means for transmitting motion to the drum, and the supply reel from which the wire is to be drawn and led to the drum through the die, of means for rendering the motion transmitting means inactive under danger conditions comprising a displacing rock arm, means tending to actuate the same, a slideable member to which the arm is connected, a detent coacting with the slideable member and normally holding the same in position to restrain the arm from action, a rock lever having a crank portion operatively connected with the detent to retract the same when the lever is rocked in one direction, an arm extending from the said rock lever, a rocking frame including a cross bar to be engaged by the body of a person close to the machine, the said frame having a member extending in proximity to the arm of the rock shaft to engage the arm and actuate the shaft when the said frame is pressed in the direction of the machine, and operative connection between the said frame and the slideable member for effecting resetting of the slideable member upon rearward swinging movement of the frame.

In testimony whereof I affix my signature.

PATRICK J. MAHONEY. [L. S.]
